DESIGN FOR A BOTTLE STOPPER

George Grunberg, New York, N. Y., assignor to
The G. G. Patent Company, Cincinnati, Ohio, a corporation of Ohio

Application February 6, 1941, Serial No. 98,805

Term of patent 7 years

To all whom it may concern:

Be it known that I, George Grunberg, a citizen of the United States, residing at New York city, in the Borough of Manhattan, county of New York, and State of New York, have invented a new, original, and ornamental Design for Bottle Stopper, of which the following is a specification, reference being had to the accompanying drawing, forming a part thereof.

The characteristic features of my design reside in a bottle stopper having the specific configuration and arrangement of parts as shown.

I claim:

The ornamental design for a bottle stopper, substantially as shown and described.

GEORGE GRUNBERG.
